UNITED STATES PATENT OFFICE.

DAVID B. MILLER, OF GREENFIELD, MASSACHUSETTS.

TAP WRENCH.

Application filed February 21, 1922. Serial No. 538,286.

To all whom it may concern:

Be it known that I, DAVID B. MILLER, a citizen of the United States of America, residing at Greenfield, in the county of Franklin and State of Massachusetts, have invented certain new and useful Improvements in Tap Wrenches, of which the following is a specification.

This invention relates to improvements in tap wrenches.

It has for an object to provide a wrench for turning or rotating and securely holding a tap, reamer, and like tools when in use, and which are provided with the usual square or rectangular shaped gripping shank.

A further object is to provide a tap wrench in which the jaws are adjusted by a screw thread having a fine pitch for providing a firm grip or hold on the shank of the tool.

A further object is to provide guiding means for the sliding movements of the jaws in order to prevent any side play of the jaws either when in use or during their adjustments in the holder.

A further object is to provide means for holding one of the jaws against movement after the tool is inserted and the other jaw is moved against the tool.

A further object is to provide novel means of attaching the movable jaw to the movable or adjustable handle.

A further object relates to the method of broaching the handles for aligning the jaws by forming grooves with flattened and circular sides.

Further objects and nature of the invention will appear in the body of the specification and will be specifically pointed out in the appended claims.

Referring to the drawings:

Fig. 1 is a plan view of the wrench with the parts in their assembled position.

Fig. 2 is a vertical sectional view in a plane represented by the line 2—2 on Fig. 1 showing the jaws as gripping the square shank of a tool, and the interior structure of the wrench.

Fig. 3 is a transverse sectional view on the line 3—3 of Fig. 1 looking in the direction of the arrows showing one of the guideways in the wrench which are formed with flat and curved surfaces.

Fig. 4 is a perspective detail view of one of the jaws with the disk-shaped end which

is always held in a fixed position when the wrench is in use, and

Fig. 5 is a detail view of the other or movable jaw that is moved toward the shank of the tool being gripped.

Referring to the drawings in detail:

1 designates the central or body portion of the wrench having the oppositely extending end portions 2 and 3. The portion 2 is internally threaded for a portion of its length as indicated at 4 and the remaining or outer end portion is left smooth or without threads, as indicated at 5.

The right hand portion 3 is formed with an internal thread for a portion of its length as indicated at 6 and the remaining or outer end, is like the portion 2, made smooth or without threads as indicated at 7. 8 and 9 are the operating handles which are threaded at their inner ends for engaging the internal threads 4 and 6 respectively. 10 and 11 designate the tool gripping jaws in Figs. 4 and 5, removed from the wrench. The jaw 10 is formed with the parallel flat faces 12 and 13 and formed with the oppositely located curved faces 14 and 15 and one end with the integral disk-shaped piece 16, the radius of which is equal to the radius of the curved faces. Its other end is formed with the faces 17 and 18 which are arranged at right angles to each other, as shown. The parallel flat faces 12 and 13 engage internally located parallel flat faces 19 and 20 in the body portion 1 when assembled as indicated in Fig. 3 in section. The curved surfaces 14 and 15 engage the curved surfaces 21 and 22 of the body portion 1. These curved surfaces are indicated in Fig. 1 by the dotted line. 23 designates a shoulder which is located at the inner end of the threaded recessed portion of the handle 2 of the portion 1 and against which shoulder the inner surface 24 of the disk-shaped member 16, jaw 10, engages when assembled.

The inner end 8' of the handle 8 engages the outer surface of the disk shaped member 16 for firmly retaining the jaw 10 against the shoulder 23. By simply removing the handle 8 the jaw 10 may be removed as readily understood.

Referring now to the construction and operation of the other jaw 11. This jaw 11 is like the other or companion jaw 10, formed with the parallel flat faces 25 and 26 and the oppositely located curved faces 27 and 28. These faces engage corresponding-

ly shaped faces or surfaces in the body portion 1 as indicated at 29 and 30 and at 31 and 32 respectively. Its inner end is formed with the notched or recessed part 33 having the tool gripping faces 34 and 35 which engage the adjacent faces of the shank of the tool indicated at 36 in place in the wrench. The outer end of the jaw 11 is formed with a T-shaped projection 37. The handle 9 is formed with an open ended recess 38 to receive this projection. This construction forms a swivel connection between the jaw 11 and the handle 9. 38' is a slot to receive the shank 37'. It is for 15 the purpose of withdrawing the jaw 11 from the holder and for enlarging the space between the inner gripping ends of the two jaws in order to receive shanks of different sizes. By turning the handle 9 left handed 20 the jaw 11 may be completely removed. The flat parallel bearing surfaces as well as the curved bearing surfaces in the body portion 1 for both of the jaws are formed by the broaching process, whereby a very accurate fit for the jaws is obtained. These sliding surfaces also possess the very important 25 advantage of maintaining accurate alignment of the gripping faces of the jaws and also serve to prevent any tendency to rotate 30 or turn thereby eliminating all side play or lost motion which is a very important feature in the construction of tap wrenches. A very firm grip is therefore maintained by the jaws on the shank 36 of the tool.

35 In operation, the handles 8 and 9 by reason of their fine pitch screw threads retains the jaws with a firm grip against the shank of the tool. Such a thread is not easily shaken loose when in use.

40 What I claim is:

1. A tap wrench comprising a body member having oppositely projecting interiorly threaded portions, two jaws in the body member, a shoulder in one of said portions 45 to serve as a stop for one of the jaws, a handle in the said portion for retaining this jaw fixed against the shoulder, a second handle in the threaded body member, the other jaw in the body member being connected to the second handle in the other threaded projecting portion by means of a 50 swivel connection between the second jaw and the second handle, and the jaws having flat cooperating surfaces with the body member to prevent rotary movement of the jaws.

2. In a tap wrench, the combination with a body portion thereof having oppositely located flat and curved surfaces, gripping jaws having correspondingly shaped surfaces engaging the same, and operating handles threaded into the body portion which engage the gripping jaws for retaining the jaws in place and one of the handles being for adjusting one of the jaws and the other handle being for retaining the other jaw in 60 a fixed position but permitting the removal of this jaw when the said other handle is removed from the body portion.

3. A tap wrench having in combination with a body portion which is formed with 70 two pairs of flat and curved surfaces therein, a shoulder in the portion, clamping jaws engaging the surfaces, handles threaded into the body portion, one of the jaws having a member engaging the shoulder, a handle for 75 retaining this jaw against the shoulder, the other jaw having a swivel connection with the other handle for moving this jaw.

4. A jaw for a tap wrench having two oppositely curved faces and two oppositely 80 located flat faces, said jaw having an integral disk-shaped piece at one end of a radius equal to the radius of the curved faces and tool gripping faces at its other end.

5. In a tap wrench, the combination, a 85 stock having a centrally located oppositely recessed part, oppositely extending portions connected to the centrally located part and each of said extending portions having an internally threaded portion, operating handles each having a threaded end adjacent thereto for engaging the internally threaded portions, tool gripping jaws in the centrally located part, a shoulder at the inner end of one of the internally threaded portions, one 90 of the jaws having a disk shaped portion at one end which engages the said shoulder and the inner end of one of the operating handles engaging the opposite side of the disk shaped portion for forcing it against 95 the shoulder, the other jaw having a T-shaped projection and the other operating handle having an open ended recess to receive said projection, whereby when the other operating handle is threaded into the 100 internally threaded part the second or other jaw may be moved towards and away from the other or fixed jaw.

DAVID B. MILLER.
